United States Patent Office.

NOAH SHAW, OF EAU CLAIRE, WISCONSIN.

Letters Patent No. 95,387, dated September 28, 1869.

IMPROVEMENT IN STEAM-GENERATORS.

The Schedule referred to in these Letters Patent and making part of the same

To all whom it may concern:

Be it known that I, NOAH SHAW, of Eau Claire, in the county of Eau Claire, and in the State of Wisconsin, have invented certain new and useful Improvements in Steam-Generators; and do hereby declare that the following is a full, clear, and exact description thereof, reference being had to the accompanying drawings, and to the letters of reference marked thereon, making a part of this specification.

The nature of my invention consists in conducting a current of water from a steam-boiler around the fire-box, by means of hollow grate-bars, generating steam in said bars, and conducting the steam back into the boiler, in a manner that will be hereinafter fully set forth; and also in the construction and use of an auxiliary grate-bar which will be fully described.

In order to enable others skilled in the art to which my invention appertains, to make and use the same, I will now proceed to describe its construction and operation, referring to the annexed drawings, in which—

Figure 1 is a vertical cross-section, and

Figure 2, a perspective view of a steam-boiler with my improvement attached.

Figure 3 is a perspective view of the auxiliary grate-bar, and

Figure 4 is a vertical cross-section, showing the manner in which the auxiliary grate-bar is used.

A represents a steam-boiler made in any of the known and usual ways, and of any size or dimensions desired.

B is the furnace or fire-place under said boiler.

On each side of the boiler A are attached three pipes—one, C, near the front end; one, D, at or near the centre; and the third, E, near the rear end of the boiler.

These pipes are all connected with the boiler on a line about the centre of the boiler, as seen in fig. 2.

The front pipe C runs horizontally outward so as to come on the outside of the furnace or fire-box, then downward perpendicularly, so that its lower end will come below the level of the fire-box.

It is then turned inward and runs under the fire-box to about the centre of the same. Here it is turned upward for a very short distance, and then placed in a tortuous position, running back and forth at the bottom of the fire-box, forming one-half of the grate, then up along the same side of the fire-box, continuing its tortuous or winding course the whole height of the same, until it, at last, connects with the centre pipe D.

The half of the grate thus formed by the tortuous pipe C is not horizontal, but slightly inclined upward toward the side, although being in a plane parallel with the boiler longitudinally, as seen in fig. 1.

There being one pipe, C, as above mentioned, on

each side of the boiler, and both running in the same manner and shape, it will be seen that the entire bottom and sides of the fire-box are thus provided with hollow grate-bars connected with the boiler.

The water in the boiler passes through the pipe C, and is, during its passage under and at the side of the fire, converted into steam, which, by the inclined position of the pipe in the bottom of the fire-box, is caused to ascend through said pipe and pass into the boiler through the pipe D.

Thus a continuous current of water may be kept passing from the boiler, this water converted into steam, and the steam and water returned to the boiler.

At a suitable point in the pipe C, is a check-valve, a, which allows the water to flow freely in the direction above described, but prevents it from going in the opposite direction if such should be its tendency.

I do, of course, not confine myself to the specific turns or bends of the pipe C, as above set forth, but desire to include any, substantially the same in its construction, whereby a current of water may be passed from the boiler through suitable means or devices embodying the elements of this invention, under and at the side of the fire, there converted into steam, and, with the water, returned to the boiler.

The pipe E also leads outward and downward from the boiler on one side, passes in rear of the fire-box, where it takes a tortuous or winding course back and forth between the bridge-wall and the boiler, inclining upward toward the other side, thence out, and enters the boiler on the opposite side from where it left the boiler. Water passes in like manner through this pipe from the boiler, is converted into steam, and in this condition, with the water, returned to the boiler. This pipe is also provided with a check-valve, b, to allow or cause the current to flow only in one direction.

Between each coil of the pipe C that forms the grate in the fire-box, is placed an auxiliary grate-bar, d, the sides of which are curved inward, as shown in figs. 3 and 4, and provided with curved ribs e e, so as to fit on the pipe C. The ribs e e are placed at any suitable distances apart, forming air or draught-holes for the fire.

The advantages of this arrangement are obvious. The grate-bars are preserved from burning out too rapidly, and are kept comparatively cool even with the hottest fire. Then more steam can be made with less fuel than in ordinary boilers, and hence the expense is materially lessened.

Having thus fully described my invention,

What I claim as new, and desire to secure by Letters Patent, is—

1. Passing a continuous current of water through

suitable devices, from a steam-boiler under and at the side of the fire, converting it into steam, and returning the steam and water into the boiler, substantially as herein set forth.

2. Passing a continuous current or water through suitable devices from a steam-boiler, between the bridge-wall and said boiler, converting it into steam, and returning the steam and water into the boiler, substantially as herein set forth.

3. Providing the fire-box of a steam-boiler with hollow grate-bars on the bottom and sides, and the space between the bridge-wall and the boiler with a tortuous pipe, all connected with the boiler, substantially as herein set forth.

4. The auxiliary grate-bar *d*, provided with ribs *ee*, constructed substantially as herein set forth.

5. Providing the fire-box *B* with one tortuous pipe, or several pipes connected together, so as to form the bottom inclined upward from the centre toward the sides, and extending up the sides, substantially as herein set forth.

6. The combination of the boiler *A* with pipes *C* and *D*, connecting said boiler with the inclined pipe or pipes running along the bottom and sides of the fire-box *B*, substantially as herein set forth.

7. One or more tortuous pipes connected together in an inclined position in the space between the bridge-wall and the boiler, substantially as herein set forth.

8. The combination of the boiler *A*, and the pipes *E* connecting said boiler, with the inclined pipe or pipes running back and forth in the space between the bridge-wall and the boiler, substantially as herein set forth.

In testimony that I claim the foregoing, I have hereunto set my hand, this 13th day of September, 1869.

N. SHAW.
